CLAIM

Mar. 19, 2015 (JP) 2015-005888
Mar. 19, 2015 (JP) 2015-005889

The ornamental design for a throw-away tip for metal cutting tool, as shown and described.

(51) **LOC (11) Cl.** **15-09**

DESCRIPTION

(52) **U.S. Cl.**

FIG. 1 is a front view of a throw-away tip for metal cutting tool showing our new design;
FIG. 2 is a rear view thereof;
FIG. 3 is a top view thereof;
FIG. 4 is a bottom view thereof;
FIG. 5 is a right side view thereof;
FIG. 6 is a left side view thereof;
FIG. 7 is a first perspective view thereof;
FIG. 8 is a second perspective view thereof;
FIG. 9 is a referential top view thereof;
